GASEOUS ELECTRIC DISCHARGE DEVICE

Hans Ewest, Berlin-Lichterfelde-Ost, and Georg Gaidies, Berlin-Pankow, Germany, assignors to General Electric Company, a corporation of New York

Application December 15, 1933, Serial No. 702,590
In Germany December 31, 1932

3 Claims. (Cl. 176—122)

The present invention relates to gaseous electric discharge devices generally and more particularly the invention relates to such devices useful as light sources in television work or the like. 5 Sodium lamps having thermionic electrodes and a gas filling are useful in television work because of the high efficiency of such lamps and the high intensity of the light emitted thereby. We have observed that sodium lamp devices do not 10 respond instantaneously to the oscillations of the current supply of the lamp which causes a blurring of the picture reproduced by the television apparatus.

The object of the present invention is to produce a lamp which responds instantaneously to the oscillations of the current supply thereof. Still further objects and advantages attaching to the device and to its use and operation will be 20 apparent to those skilled in the art from the following particular description.

We have discovered that the addition of a small amount of mercury, up to about 10%, to the sodium in a rare gas filled sodium lamp having thermionic electrodes makes such lamps instantaneously responsive to the oscillations of the current supply of the lamp. We find it desirable that the quantity of mercury in the lamp be such that substantially all the mercury is in a vaporous condition at the operating temperature of the 30 lamp. Where the operating temperature of the lamp is 400° C. or higher the mercury can be 1% or less of the sodium. For operating temperatures of approximately 300° C. an addition of 4 to 5% of mercury to the sodium is desirable. In any case it is preferable that the quantity of mercury be such that the sodium spectrum predominates in the spectrum of the light emitted by the lamp for under these conditions the high efficiency and high intensity light emission characteristics of sodium lamps are retained.

In the drawing accompanying and forming part of this specification an embodiment of the invention is shown in a side elevational view, but as such illustration is primarily for purposes of disclosure it will be understood of course that numerous changes in the form and details of the device and in its use and operation may be made by those skilled in the art without departure from the broad spirit and scope of the invention.

50 Referring to the drawing the new and novel gaseous electric discharge device comprises a container 1 having thermionic electrodes 2 and 3 sealed therein. Said electrodes 2 and 3 consist of a rod of electron emitting material, such as 55 barium oxide, surrounded by a filamentary metal

heating coil, such as a tungsten filament. Said container 1 has a gaseous atmosphere therein comprising a starting gas, such as argon or neon, or a mixture of such gases; a difficultly vaporizable material, such as sodium, indicated at 4, and 60 a quantity of mercury, indicated at 5. The amount of mercury in relation to the amount of sodium introduced into the lamp depends upon the temperature of the container 1 during the operation of the lamp device as set forth above. 65 We prefer that the amount of mercury in the lamp be such that substantially all of this material is in a vaporous condition during the operation of the lamp and that the mercury should not be in excess of about 10% of the sodium in any 70 case in order that the lamp retain the high efficiency and intense light emission characteristics of a sodium lamp.

While we have shown and described the mercury as being introduced into the container 1 75 separately from the sodium it will be understood, of course, that we contemplate that the mercury can be introduced into the lamp in the form of sodium amalgam the above proportions being observed.

80 The container 1 is maintained at the high temperature required for an effective vapor pressure of the difficultly vaporizable material during the operation of the device by the high current density discharge therein made possible by the use 85 of thermionic electrodes 2 and 3. When desired, the container 1 is provided with a heat conservator to assist in maintaining said container 1 at a high temperature during the operation of the device. A suitable heat conservator is a 90 double walled, evacuated jacket, or a single walled jacket having a gas of poor heat conductivity therein enclosing said container 1. When desired, the container 1 has baffles interposed between the electrodes 2 and 3 and the stem parts 95 of said container 1 completely closing off said stem parts from the other parts of said container 1 to protect said stem parts from the effects of the metal vapor in the lamp device. It will be understood, of course, that the shape of the container 1 can be changed to suit the needs of the service to which the lamp is to be put, for example, a bulb shaped container is desired in many applications of the lamp.

100 What we claim as new and desire to secure by Letters Patent of the United States is:—

1. An electric discharge device comprising a container, electrodes sealed therein, a gaseous atmosphere therein comprising a starting gas, a difficultly vaporizable material and mercury, the 110

mercury being approximately 10% of the difficultly vaporizable material.

2. An electric discharge device comprising a container, electrodes sealed therein, a gaseous atmosphere therein comprising a starting gas, a difficultly vaporizable material and mercury, the mercury being approximately 1 to 10% of the difficultly vaporizable material.

3. An electric discharge device comprising a container, electrodes sealed therein, a gaseous atmosphere therein comprising a starting gas, sodium and mercury, the mercury being approximately 1 to 10% of the sodium.
